J. C. PATTERSON

CLIPPING IMPLEMENT

Filed Aug. 21, 1924

FIG. I.

FIG. IV.

FIG. II.

FIG. III.

WITNESSES:

James H. Bell,
Alfred E. Schlinger.

INVENTOR:
John C. Patterson,
BY Tracy Paul
ATTORNEYS.

UNITED STATES PATENT OFFICE.

JOHN C. PATTERSON, OF PHILADELPHIA, PENNSYLVANIA.

CLIPPING IMPLEMENT.

Application filed August 21, 1924. Serial No. 733,339.

To all whom it may concern:

Be it known that I, JOHN C. PATTERSON, a citizen of the United States, residing at Philadelphia, in the county of Philadelphia and State of Pennsylvania, have invented certain new and useful Improvements in Clipping Implements, of which the following is a specification, reference being had to the accompanying drawings.

10 This invention relates to clipping implements and more particularly to that type useful in financial institutions for detaching coupons from bonds and stock certificates, the primary object being to provide a novel 15 cutting instrument especially serviceable for the foregoing mentioned use.

Another object of this invention is to provide an implement of the above typified character embodying means for temporarily 20 holding the severed coupon or other portion cut off, said means being capable of retaining a succession of clipped coupons without fear of loss or accidental displacement, and also movable into out-of-service location 25 when it is not desired to collect a number of severed coupons, whereupon the implement may be used as an ordinary angular shears.

Other objects and attendant advantages 30 will appear as the following description of a practical embodiment of my invention proceeds, the same having been chosen from other possible forms as most conveniently illustrating the novel features involved.

For a full understanding of this invention 35 reference is made to the accompanying sheet of drawings, constituting a part of this specification, and in which like characters of reference designate corresponding parts in all the views.

40 Fig. I, is a perspective view of my novel clipping implement.

Fig. II, is an enlarged sectional detail of the coupon or other severed portion collecting means in service location.

45 Fig. III, is a similar sectional view showing the collecting means in the out-of-use position; and,

50 Fig. IV, is a detail view illustrative of the manner in which a series of coupons are retained and the holder therefor swung outwardly for the removal of said coupons.

Referring to the drawings my novel clipping implement comprises a pair of finger bows 4, 5 having integral shear blades 6, 7 respectively fulcrumed together by means of a pivot pin 8, or the like. One of the

shear blades 6—for example—which is uppermost in use is laterally directed to provide an integral or attached shear extension 9; and in the angular space intervening said 60 blade 6 and extension 9 I fit a brace plate 10 conveniently flanged for secure connection in situ by rivets or screws 11. This brace plate 10 is preferably, though not essentially, disposed in a plane closely adjacent the shear edges of the blade 6 and its extension 9, and it functions as a presser and steadyng means for the coupon or other portion cut off from a bond or stock certificate during severance, and for a purpose 70 later on explained.

To the other shear blade 7 there is securely attached, in any appropriate manner, a complemental shear extension 12 adapted for cooperation with the extension 9 aforesaid, as later on more fully set forth, and it will be readily understood that when pressure is exerted on the finger bows 4, 5 the shear blades 6, 7, and extensions 9, 12 respectively will effect a gradual and clean cut 75 by the intimate shearing engagement of the cutting edges of said blades and extensions.

Attached to the shear blade 7 by means of a screw or screws 13—or rivets—is one arm 14 of an angled bracket, the other arm 15 whereof is longitudinally channeled or slotted and fitted with a flat spring 16 conveniently secured in place by a pin 17, as will be readily understood by those acquainted with the art. Or, the spring 16 80 may be otherwise mounted so long as the major portion thereof is left free for flexure between the opposed walls of the slotted arm 15. Pivotaly mounted at the free end of the arm 15 by means of a pin 18 is an impaling prong 19 having a rectangular section heel 20 and projecting finger 21; whereby said impaling prong may be moved into operative position as shown in Figs. I and 90 II, or disposed between the opposed walls of the arm 15 in out-of-service location—as indicated in Fig. III—when the finger 21 will occupy a substantially vertical position.

It will be obvious that the free end of the flat spring 16 cooperates with the flat faces of the heel 20 to retain the impaling prong 19 in either of the positions referred to. Again the impaling prong 19 may be swung on its pivot 18 into a position co-extensive with the arm 15,—when 105 a series of severed coupons "C" collected thereon are ready for removal—whereupon 110

on the finger 21 will occupy a reversely directed position as shown in Fig. IV and be prevented from further turning movement in a clockwise direction, as viewed in Fig. I, by the free end of the spring 16 abutting thereagainst. In other words, the impaling prong 19 is capable of movement through a semi-circle to the left or right hand by a two stage progressive step. It is to be noted, that the impaling prong 19 is needle pointed and of a length to enter through a registering hole 22 provided for the purpose in the brace plate 10, when the implement is operated or closed for severance purposes.

In operation it will be apparent that as the finger bows 4, 5 are moved towards each other the shear blades 6, 7 will be closed upon one another, followed by a complementary action of the extensions 9, 12, thereby effecting a rectangular cut, with the severed portion automatically impaled upon the prong 19 under pressure action exerted by the brace plate 10 prior to completion of the shearing action. As a result the severed coupon or other portion of material cut-off will be prevented from falling whenever the prong 19 occupies the position shown in Figs. I and II.

From the foregoing description it is thought the advantages of my improved clipping implement will be fully appreciated without further detailed explanation, and while I have shown a preferred embodiment of the invention, it will be apparent that minor detail changes may be adopted without departing from the scope of the appended claims.

Having thus described my invention, I claim:

1. A clipping implement comprising co-operating shear blades having angularly directed extensions, one of said blades and the extension thereof including an apertured brace, and a spring influenced impaling prong pivotally supported in a channeled projection on the other shear blade with capacity for retention in registration

with an aperture in the aforesaid brace and accommodation in the channeled projection when not in use.

2. A clipping implement comprising co-operating shear blades having angularly directed extensions, one of said blades and the extension thereof including an apertured brace, a channeled lateral projection on the other shear blade, and a spring influenced impaling prong pivoted therein with capacity for arrest in registration with the aperture of the aforesaid brace, or disposition in the channeled projection or co-extensive therewith for the purposes specified.

3. A clipping implement comprising co-operating shear blades having angularly directed extensions, one of said blades and the extension thereof including an apertured brace, a slotted lateral projection on the other shear blade, a spring influenced impaling prong pivoted therein, and means whereby said prong may be manipulated a quarter-turn into the operative or inoperative position.

4. In a clipping implement including angled shear blades and an apertured support associated in one blade, the combination with the other blade of a slotted lateral projection, and pivoted impaling prong having capacity for arrest in registration with the aperture of the aforesaid support or disposal out of alignment therewith.

5. In a clipping implement including angled shear blades and an apertured support associated in one blade, the combination of a slotted projection on the other blade, and a spring controlled impaling prong pivotally carried by said projection with capacity for arrest in registration with the aperture of the aforesaid support or retention in locations at right angles thereto.

In testimony whereof, I have hereunto signed my name at Philadelphia, Pennsylvania, this 19th day of August, 1924.

JOHN C. PATTERSON.
